UNITED STATES PATENT OFFICE.

LOUIS M. PIER AND MICHAEL H. FOSTER, OF NEWARK, NEW JERSEY.

PRINTING-PRESS.

1,048,094.

Specification of Letters Patent.

Patented Dec. 24, 1912.

Application filed January 31, 1912. Serial No. 674,610.

To all whom it may concern:

Be it known that we, LOUIS MORRIS PIER and MICHAEL HALL FOSTER, citizens of the United States, residing at Newark, in the county of Essex and State of New Jersey, have invented certain new and useful Improvements in Printing - Presses, of which the following is a specification, reference being had to the accompanying drawings.

10 This invention relates to improvements in printing presses and particularly to improvements in printing presses for printing upon a continuous web of paper, such as is used in the manufacture of paper bags, for example; and an object of this invention is to provide a printing press of the type just referred to which will be simple in construction, comparatively cheap in manufacture and most efficient and durable in operation 20 and use.

Another object of this invention is to provide a printing press in which the ink rolls will, during the operation of the press, be kept continuously rotating in order that the 25 ink may be evenly and thoroughly distributed.

In the drawings illustrating the principle 30 of this invention and the best mode now known to us of applying that principle, Figure 1 is a front elevation of our new printing press; Fig. 2 is a side elevation of the same, looking in the direction of the arrow A of Fig. 1; and Figs. 3 and 4 are sections on the lines B-B and C-C, respectively of 35 Fig. 1.

The frame of the machine consists essentially of two side standards *a* to each of which is attached a bracket *b*. Journaled in the base portions of the side standards *a* 40 are the ends of the driving shaft *d* upon which is mounted fast the driving pulley *e* adapted to be belt connected to any suitable source of power (not shown). To the top of each of the side standards *a* is fastened 45 one end of a hanger *f* the other end of which is fastened to an end of the ink-container *g*, which may be of any suitable type. In an opening *h* in each of the side standards *a* there is mounted free to slide a block *i* 50 formed with guide-ribs *h'*, which project into channels formed in the side walls of the opening *h*. Each of the slide-blocks *i* is formed with a recess *k* in which is journaled an end of the shaft *m* which carries 55 the ink-receiving roll *n*. In each of the slide-blocks *i* immediately below the recess

k there is formed a recess *k'* which is similar to the latter and in which is journaled an end of the shaft *o*, which carries the ink-distributing roll *p*. Between one end of the latter and the adjacent side standard *a* there is mounted fast upon the shaft *o* a pulley *q* which is connected by the endless belt *r* with a pulley *s* mounted fast upon one end of the driving shaft *d*. The belt *r* passes over a pair of rolls *u* of a belt tightener *t*. The rolls *u* are mounted in a fork-like frame *v* having a stem or a plunger *v'* which is slidably mounted in a bracket *w* and is formed with a collar *v''* between which and the opposed side of the bracket *w* there is interposed a coil spring *x* which tends to force the plunger *v'* outwardly from the bracket against the tension of the belt *r*. Upon each end of the shaft *d* there is 75 mounted an eccentric *y* upon which rests a roller *z* which is carried by the lower end of a slide-block *2*, which is mounted in an opening *h'* in the bottom of one of the standards *a* and is connected with the slide-block *i* directly above it by means of a two-part pitman or connecting-rod *3*. By means of a turn-buckle *3'* the inner opposed ends of the two parts *3', 3''* of the two-part pitman *3* are joined. By turning the turn-buckle, the slide-blocks *i, 2* may be adjusted 80 toward and from each other to allow for different sizes of the plate-roll hereinafter to be described.

Journaled in the side standards *a* are the 90 ends of a shaft *4* upon which are mounted the bed-roll *5* and, at one end thereof, a pulley *6* and a spur gear *7*. The pulley *6* is connected by an endless belt *8* with the pulley *9* mounted upon the end of the driving shaft *d* opposite that on which is mounted the pulley *s*. The gear *7* meshes with a gear 95 10 mounted fast upon a shaft *11*, which is arranged directly above the shaft *4* and the ends of which pass through openings *h''* 100 in the side standards *a*. Upon the shaft *11* is mounted the plate-roll *12* which carries the type-block or type-plate (not shown).

Each side standard *a* is provided with brackets *13* formed with threaded openings through which passes a vertically-disposed rod *14* having its upper portion threaded and its upper end provided with a hand wheel 15 and its lower end with a fork *16* which straddles one end of the shaft *11* which carries the plate-roll *12*. By turning the hand wheels *15* the pressure upon the plate-roll 110

shaft may be varied and the pressure of the plate-roll 12 on the bed-roll 5 changed.

The roll X of paper is supported on a spindle c and from it is led a web Y which passes between the plate-roll 12 and the bed-roll 5. One end of the spindle c is journaled and is free to slide lengthwise in the journal-box c' carried by one of the brackets b, while its other end is formed with a collar 10 c'' having a groove c* in which is mounted a fork 17 from which projects through a slot in the bracket b a stem 18 formed at its lower end with a threaded opening. Through the latter passes the threaded portion 15 of a screw shaft 19 which is carried by the bracket b and one end of which is provided with a hand wheel 20. By turning the latter the spindle c may be shifted back and forth to adjust the position of the roll X.

20 As the shaft d rotates, the ink-rolls n, p, move up and down, as will be readily understood from the foregoing description taken in connection with the accompanying drawings. The ink-receiving roll n at the 25 end of the upward movement of the slide-blocks i touches the bottom of the ink-container g and thus receives a charge of ink, which is transferred to its coacting roll p. This ink-distributing roll p at the end of 30 the downward movement of the slide-blocks i touches the type-block or type-plate (not shown) on the plate-roll 12, for the purpose of inking the same. Since the ink-rolls n, p are kept continuously rotating, the ink will 35 be evenly and thoroughly distributed.

We claim:

1. A printing-press comprising a plate-roll; a bed-roll; a driving-shaft which is connected with and drives one of said rolls; 40 a pair of ink-rolls; an ink-container; reciprocating mechanism which is driven by said driving-shaft and which moves one of said ink-rolls into and out of contact with said ink-container and the other of said 45 ink-rolls into and out of contact with one of the first-named rolls; and mechanism which is actuated by said driving-shaft and which drives said ink-rolls continuously while the same are maintained in active 50 operative relation to the first-named rolls by

said reciprocating mechanism, in the normal printing operation of the press.

2. A printing-press comprising a plate-roll; a bed-roll; a driving-shaft which drives said rolls; a pair of ink-rolls; an ink-container; reciprocating mechanism which moves one of said ink-rolls into and out of contact with said ink-container and the other of said ink-rolls into and out of contact with said plate-roll; and mechanism which keeps 55 said ink-rolls continuously rotating, while said reciprocating mechanism moves one of the same into and out of contact with said ink-container and the other thereof into and out of contact with said plate-roll, in the 60 normal printing operation of the press.

3. A printing press comprising a plate-roll; a bed-roll; an ink-container; a pair of ink-rolls; reciprocating mechanism which reciprocates the latter between said plate-roll and ink-container; a driving mechanism; a belt which connects one of said ink-rolls with said driving mechanism and which maintains said ink-rolls rotating continuously during the operation of said reciprocating mechanism; and a belt-tightener 70 over which said belt passes.

4. A printing press comprising a plate-roll; a bed-roll; an ink-container; a pair of slide-blocks in which said ink-rolls are 80 mounted free to rotate; a second pair of slide-blocks; mechanism for reciprocating the latter; connecting devices for connecting the first-named pair of slide-blocks with the other pair of slide-blocks; a driving 85 mechanism; a belt which connects said driving mechanism with one of said ink-rolls and which keeps said ink-rolls continuously rotating during the operation of said reciprocating mechanism; and a belt tightener over 90 which said belt passes.

Signed at Newark, New Jersey, this twenty-seventh day of January, 1912, in the presence of the two undersigned witnesses.

LOUIS M. PIER.
MICHAEL H. FOSTER.
